CLAIM

The ornamental design for an accessory for robot toy, as shown and described.

DESCRIPTION

FIG. 1 is a front elevational view of the accessory for robot toy;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a cross-sectional view taken along line 8-8 in FIG. 5; and,

FIG. 9 is a reference view showing the accessory for robot toy in use.

The broken lines depict environmental subject matter, and thus form no part of the claimed design.
